My

UNITED STATES PATENT OFFICE.

FRANCIS P. McCOLL, OF ST. ANDREWS, NEW BRUNSWICK, CANADA, ASSIGNOR TO
AMERICAN KEY CAN COMPANY, OF CHICAGO, ILLINOIS, A CORPORATION OF
NEW JERSEY.

ROLL-CAP.

1,082,280.

Specification of Letters Patent. Patented Dec. 23, 1913.

Application filed August 25, 1910. Serial No. 578,874.

To all whom it may concern:

Be it known that I, FRANCIS P. McCOLL, a citizen of the United States, residing at St. Andrews, New Brunswick, in the Dominion of Canada, have invented a certain new and useful Improvement in Roll-Caps, and declare the following to be a full, clear, and exact description of the same, such as will enable others skilled in the art to which it pertains to make and use the same, reference being had to the accompanying drawings, which form a part of this specification.

My invention has for its object to produce a closure for openings in cans or other receptacles which may be rolled up on a key so as to uncover the openings regardless of the size of the openings or their size relative to the can head or other part in which they are located.

The various features of novelty whereby my invention is characterized will herein-after be pointed out with particularity in the claims; but for a full understanding of my invention and of its object and advantages, reference may be had to the following detailed description taken in connection with the accompanying drawing, wherein:

Figure 1 is a plan view of a can having a closure arranged in accordance with a preferred form of my invention; Fig. 2 is a central section taken on line 2—2 of Fig. 1; Fig. 3 is a section taken on line 3—3 of Fig. 1; and Fig. 4 is a section through the tongue on line 4—4 of Fig. 1.

For the sake of brevity I have illustrated my invention as applied only to a can having an opening therein smaller than the diameter of the can body; but I do not desire to be limited to this particular field since my invention is applicable to the closing of openings of various different kinds and in various different receptacles. Furthermore my invention is not limited in its application to receptacles for it is adapted to close openings in partitions or walls used for any purpose.

Referring to the form of my invention and the use illustrated in the drawing, A represents a can having in the head thereof an opening B. The can head is depressed about the opening so as to form an annular V-shaped groove C adjacent to and surrounding the opening.

D is a cap of a size and shape to close the

opening and fill the area bounded by the groove. In accordance with my invention I form on the cap a depending annular flange E which flares outwardly as it recedes from the cap and fits closely over the inner wall of the groove. The free edge of the flange is turned up and out, as at F, so as to form a narrow annular fin which rests upon the outer wall of the groove near the bottom of the groove.

The cap may be soldered in place in any suitable way, this being conveniently accomplished by passing it through any usual form of soldering machine. By providing the cap with a tongue projecting therefrom at a point adjacent to the fin, the tongue may be inserted in the key and wound thereon until the soldered joint is reached. The small up-turned fin is in just the right position to permit the solder to be torn readily as soon as the strain comes on that portion thereof adjacent to the tongue and, after the joint has once started to tear, no difficulty is experienced in progressively rolling up the cap and tearing the entire joint as the rolling proceeds. The portions of the fin immediately adjacent to the tongue facilitate the starting of the tear, while the remainder of the fin always brings a portion of the soldered joint into a plane which is weakest under the strains imposed by the rolling process. Therefore the fin will provide new starting points all along the joint so that, as the rolling progresses, the joint will be continually attacked at points offering the least resistance.

In the preferred arrangement the tongue is a continuation of the flange on the cap and projects from the free edge thereof as indicated at G. Furthermore I prefer to carry the fin partially along the sides of the tongue as indicated at f so that the base of the tongue will be stiffened and a good grip will be obtained upon the fin before the actual process of severing the main joint is begun. The tongue is of course bent upwardly so as to carry its free end above the groove and it may then be bent laterally so as to lie against the head of the can.

While I have illustrated and described with particularity only a single preferred form of my invention I do not desire to be limited to the specific details so illustrated and described; but intend covering all constructions and arrangements which fall within

the terms employed in the definitions of my invention constituting the appended claims.

What I claim is:

1. A roll cap comprising a disk having an annular depending flange, said flange flaring outwardly as it recedes from the disk, a tongue projecting from the flange, and the free edge of the flange being turned up so as to form a slight narrow fin encircling the flange.
2. A roll cap comprising a disk having an annular depending flange, said flange flaring outwardly as it recedes from the disk and having a tongue projecting therefrom, the free edge of said flange and the sides of the tongue adjacent to the flange being bent upwardly so as to form a slight narrow fin encircling the flange and extending at least partially along the sides of the tongue.
3. A roll cap comprising a disk having a depending annular flange, said flange flaring outwardly as it recedes from the disk, a narrow tongue projecting from the free edge of the flange, and the edge of the flange and the adjacent portions of the sides of the tongue being bent upwardly so as to form a narrow fin encircling the flange and extending at least partially along the sides of the tongue.
4. In combination, a member having an opening therein, there being in said member a groove or depression surrounding said opening, a cap adapted to close said opening, said cap having a flange shaped to extend into said groove or depression, the free edge of said flange being bent outwardly so as to form a slight narrow fin, and a tongue projecting from said flange at a point adjacent to said fin.
5. In combination, a member having an opening therein, said member having a groove V-shaped in cross section surrounding said opening and in proximity to said

opening, a cap adapted to close said opening, said cap having a depending flange shaped to fit over the inner wall of said groove, the free edge of the flange being turned upwardly so as to form a slight narrow fin engaging with a portion of the outer wall of said groove, and a tongue projecting from said flange at a point adjacent to said fin.

6. In combination, a member having an opening therein, said member having a groove V-shaped in cross section surrounding said opening and in proximity to said opening, a cap adapted to close said opening, said cap having a depending flange shaped to fit over the inner wall of said groove, the free edge of the flange being turned upwardly so as to form a slight narrow fin engaging with a portion of the outer wall of said groove, and a tongue projecting from said flange at a point adjacent to said fin, said tongue being bent upwardly so as to extend above the top of the groove.

7. In combination, a member having an opening therein, said member having a groove V-shaped in cross section extending around said opening, a cap arranged to close said opening and extend into proximity to said groove, said cap having a depending flange shaped to fit over the inner wall of said groove, a tongue projecting from the free edge of said flange and extending upwardly out of the groove, the free edge of the flange being bent upwardly so as to form a narrow fin engaging with the outer wall of said groove, said fin extending at least partially along the sides of the tongue.

In testimony whereof, I sign this specification in the presence of two witnesses.

FRANCIS P. McCOLL.
